E. ALLZEIT

PISTON VALVE

Filed Feb. 26, 1926

*Inventor:
Emil Allzeit.*

*By William C. Linton.
Attorney.*

UNITED STATES PATENT OFFICE.

EMIL ALLZEIT, OF KONIGSBERG, GERMANY.

PISTON VALVE.

Application filed February 26, 1928, Serial No. 90,837, and in Germany May 24, 1924.

The present invention relates to piston valves for steam engines principally designed to be used in connection with locomotives, and has for an object to provide an 5 automatic equalization piston valve having two different and distinct sets of steam passages in each piston head designed to allow the admission of steam from the steam inlet chamber into the steam cylinder, also to 10 equalize the difference between the pressure in the exhaust chamber and the pressure in said inlet chamber, when the pressure in the latter sinks below a predetermined minimum and adapted to permanently maintain a 15 communication between the exhaust chambers, the inlet space and both sides of the cylinder when the operating medium is shut off.

Another important object of the invention 20 resides in the provision of independent preferably spring actuated means for each piston head serving for closing the passages in said heads when the pressure in the steam inlet chamber surpasses a predetermined maximum.

It is also amongst the desideratum of the invention to provide a piston valve wherein the steam passages for equalizing the difference of pressure are essentially formed in a 25 same plane as the inlet channels or steam passages of said piston valve to the cylinder, whereby when the engine runs idle, as when the locomotive runs down an incline at high speed, free equalizing pressure is created, absolutely preventing the sucking in of smoke, dirt and the like into the inlet chamber, through the different passages in the piston valve.

Other important objects of the invention 40 will be in part obvious and in part pointed out hereinafter.

In order that the invention and its mode of operation may be readily understood by those skilled in the art to which it appertains, I have in the accompanying illustrative drawings and in the detailed following description based thereupon, set out one possible embodiment of the invention.

In these drawings is illustrated a vertical 50 cross section through the improved equalizing piston valve mounted on an engine cylinder, a portion of which is also shown in cross section.

Having more particular reference to the 55 drawings, wherein like characters of refer-

ence will designate corresponding parts throughout, I have shown an engine cylinder *a* of the type generally used in locomotives, and having a piston *s* mounted for movement therein. Secured in the usual manner to the cylinder *a* and having communication therewith by means of the combined intake and exhaust ports *i* formed at each end of said cylinder is a valve casing *g*. This valve casing has its opposed end opened to form the exhaust chambers *c* communicating with each other through a pipe (not shown) or any other suitable and convenient means known in the art. The central portion of the valve casing *g* is provided with an annular steam inlet chamber *b* communicating with the supply pipe *k*.

Mounted to reciprocate within the casing *g* is the piston rod *r* carrying the valve piston heads *h* arranged adjacent the combined intake and exhaust ports *i* and adapted to control the flow of motor fluid or steam coming from the inlet chamber *b*, to said ports as well as to permit steam to pass to the exhaust chambers *c*.

Formed within said piston heads is a set of steam passages *f* terminating at one end in an annular channel having at times communication with the intake and exhaust ports *i* for the admission of motor fluid or steam from the inlet chamber *b* into the cylinder *a*. Another similar set of concentrically arranged steam passages *e* is also formed in the piston heads *h* and extend completely therethrough. The steam passages *e* form 85 means of communication between the inlet chamber *b* and the exhaust chambers *c* permitting the equalization of pressure in said chambers.

For the purpose of controlling the amount 90 of steam passing through the different passages *e* and *f*, I provide for each piston head *h* an independently operated valve *d* shiftably mounted upon the piston rod *r*, and adapted to contact with its respective piston head. The contacting face of the valves *d* are preferably provided with a plurality of suitable packing rings *p*, so that a firm and tight connection between each valve and its respective piston head will be had. The valves *d* are normally maintained open or away from the piston heads *h* by any suitable or convenient means, but preferably, as shown in the drawings by a spring *m* retained within each valve on the piston rod *r*. 100 105 110

The inward movements of the valves *d* are limited by collars *d'* formed with or otherwise secured to the piston rod *r*.

From the foregoing description, it will be obvious to those skilled in the art, that the motor fluid or steam entering the inlet chamber *b* through the supply pipe *k'*, will alternately enter into each end of the cylinder *a* through the steam passages *f* formed 5 in each reciprocating piston head *h*, when the latter passes over its adjacent port *i*. Likewise, the exhaust steam will alternately leave through the ports *i* from the opposite ends of the cylinder *a* into the adjacent exhaust chambers *c* wherein the exhaust will 10 meet with the steam passing from the openings *e* of the piston heads.

It will also be understood that the valves *d* are kept or maintained in open position 20 by means of the springs *m* as long as the pressure in the steam inlet chamber *b* does not become too high. However, it is obvious that when the pressure does increase and become too high the valves will be forced 25 outwardly and close the passages in the piston heads *h*, but as soon as the pressure again reduces the valves *d* will be automatically opened through the force and action of the spring *m*.

It will also be understood that as long as 30 the valves *d* are kept away from their piston heads *h* the passages *e* will remain open and will effect a pressure equalization between the exhaust spaces *c* and the steam inlet 35 chamber *b*. This communication between the exhaust and inlet chambers will also take place during part of the stroke, while the steam passages *f* will be closed because of the same being covered by the wall of the 40 valve casing *g* in which the piston heads *h* are reciprocating.

Because of its simple construction, my improved piston valve is very reliable in service and cheap to manufacture and will also permit an easy replacement of parts.

It will be understood by those skilled in the art that, by the special arrangement and construction of the device with its valves *d* operating independently from each other, I 50 have realized a great advantage in that should one of the valves be damaged or otherwise become inoperative the other or remaining valve will effect the pressure equalization, which will not in any manner be hindered.

Manifestly, the construction shown is capable of considerable modification and such modification as is within the spirit of my claims, I consider within the scope of my 60 invention.

I claim:

1. A piston valve for steam engines comprising in combination with a cylinder a valve casing having steam inlet and exhaust

chambers therein and communicating with both sides of the cylinder, a double headed piston having two distinct sets of steam passages formed therein and reciprocating in said valve casing; one set of said passages for admitting steam from the steam inlet chamber into the cylinder, the second for equalizing the difference between the pressure in the exhaust chambers and the pressure in the steam inlet chamber when the pressure in the latter sinks below a predetermined minimum, said two sets of steam passages adapted to permanently maintain the communication between the exhaust chambers, the inlet chamber and both sides of the cylinder when the steam is shut off, and independent means, for each piston head, serving for closing the passages in the piston heads when the pressure in the steam inlet chamber surpasses a predetermined maximum.

2. A piston valve for steam engines comprising in combination with a cylinder, a valve casing having a steam inlet and exhaust chambers therein and communicating with both sides of the cylinder, a double headed piston having two distinct sets of steam passages formed therein and reciprocating in said valve casing; one set of said passages for admitting steam from the steam inlet chamber into the cylinder, the second for equalizing the difference between the pressure in the exhaust chambers and the pressure in the steam inlet chamber when the pressure in the latter sinks below a predetermined minimum, said two sets of steam passages adapted to permanently maintain the communication between the exhaust chambers, the inlet chamber and both sides of the cylinder when the steam is shut off and communicating with both sides of the cylinder, and an independent spring actuated valve for each piston head serving for closing the passages in the piston heads when the pressure in the steam inlet chamber surpasses a predetermined maximum.

3. A piston valve for steam engines, comprising in combination with a cylinder, a valve casing mounted on said cylinder and having communication therewith, said casing carrying an exhaust chamber at each of its opposite ends and a steam inlet chamber formed therebetween, a double headed piston reciprocating in said casing, each head of said piston having two sets of steam passages, one communicating with the steam inlet chamber and the cylinder and the other communicating the steam inlet chamber with the exhaust chambers, and independently operated valves adapted to have contact at times with such piston head for closing said passages.

In testimony whereof I affix my signature,
EMIL ALLZEIT.
